DESIGN FOR A FRAME FOR A BAG OR SIMILAR ARTICLE

Herbert Rubin, New York, N. Y.

Application November 15, 1937, Serial No. 72,863

Term of patent 3½ years

To whom it may concern:

Be it known that I, Herbert Rubin, a citizen of the United States, residing at 984 Sheridan Avenue, New York, in the county of Bronx and State of New York, have invented a new, original, and ornamental Design for a Frame for a Bag or Similar Article, of which the following is a specification, reference being had to the accompanying drawing, forming part thereof, wherein—

Fig. 1 is a side elevation of a frame for a bag or similar article, and

Fig. 2 is a top plan view thereof.

I claim:

The ornamental design for a frame for a bag or similar article, substantially as shown.

HERBERT RUBIN,
